UNITED STATES PATENT OFFICE.

WILLIAM L. TAYLOR AND CHARLES F. RICHARDS, OF BATTLE CREEK, MICHIGAN, ASSIGNORS TO JOHNSON AUTOMATIC SEALER CO., LTD., OF BATTLE CREEK, MICHIGAN, A PARTNERSHIP ASSOCIATION LIMITED OF MICHIGAN.

FLAP LIFTER FOR CARTON-SEALING MACHINES.

Application filed October 14, 1921. Serial No. 507,686.

To all whom it may concern:

Be it known that we, WILLIAM L. TAYLOR and CHARLES F. RICHARDS, citizens of the United States, and residents of Battle Creek, Michigan, have invented new and useful Improvements in Flap Lifters for Carton-Sealing Machines, which invention is fully set forth in the following specification.

This invention relates to flap-supporting and glue-applying devices and it has for its object to provide an improved mechanism of this character which overcomes serious defects and disadvantages inherent in mechanisms heretofore employed for this purpose.

It has heretofore been proposed to support the carton flaps on rollers positioned under the glue-applying devices, the cartons being fed past these devices for application of the glue to the flaps thereof and subsequently fed to flap closing and sealing mechanism.

Devices of this type are objectionable because of the large quantity of glue consumed for the reason that it is necessary to carry a heavy coating on the glue-applying devices in order to completely cover the flaps. Further, when pressure is subsequently applied to seal the cartons, the glue is forced out between the flaps and onto the cartons.

One of the objects of the present invention is to overcome these defects and disadvantages by providing flap-supporting devices operating to exert yielding pressure on the flaps while the same are supported in contact with the glue-applying devices, thus insuring complete coating of the flaps and the application of a thin coating of glue; and, at the same time, by reason of the yielding of the flap supporters, preventing jamming of the cartons and damage to the devices.

A further object of the invention is to provide flap-supporting and glue-applying devices arranged and constructed to prevent the former from coming in contact with the latter whereby disfiguration of the cartons is prevented, by provision of automatic means for controlling the movements of the flap-supporting devices by the presence of a carton to be sealed.

The invention in its preferred embodiment comprises driven glue-applying and flap-supporting devices arranged adjacent the carton conveying mechanism, the flap-supporting devices being vertically adjustable and adapted to exert yielding pressure on the extended flaps of the cartons while the flaps are in contact with the glue-applying devices whereby the flaps are entirely covered with a thin coat of glue. The flap-supporting devices are rotatably mounted on the frame of the machine and include driven shafts having flanges secured thereto which carry arcuate-shaped flap-supporting members of such length and configuration as to be completely covered by the flaps during the application of the glue thereto, the timing of the flap-supporting devices and the conveyer mechanism being such that, when each carton is in position to be operated on by the glue-applying devices, the arcuate-shaped flap-supporting members are in their uppermost position to thereby support the carton flaps in contact with the glue-applying devices. The arcuate shape of the flap supporting members insures substantially a line contact between the carton flaps and the glue rollers whereby curving or curling of the flaps is prevented when the same are engaged by these devices.

The flap-supporting devices are driven from the conveyer mechanism and a detector device is provided that engages the successive cartons to automatically maintain the driving connections aforementioned. Preferably, the detector device is provided with finger adapted to engage recesses on unoccupied forms of the conveyer mechanism to thereby move a stop member into the path of travel of a pawl on a clutch that controls the drive to the flap supporters and thereby disconnects said drive and prevents movement of the flap-supporting devices.

The invention is capable of receiving a variety of mechanical expressions, one of which, for the purpose of illustrating the invention, is shown in the accompanying drawing, wherein

Fig. 1 is a side elevation of one end of 100 a carton sealing device embodying the present invention;

Fig. 2 is a cross section on the line 2—2 of Fig. 1 looking in the direction of the arrows;

Fig. 3 is a section on the line 3—3 of Fig. 1;

Fig. 4 is a perspective view showing the improved device;

Fig. 5 is a detail perspective showing one of the flap supporters;

Fig. 6 is a sectional view through the clutch that controls the drive to the flap supporters;

Fig. 7 is a side elevation corresponding to Fig. 6; and

Fig. 8 is a sectional detail of the stop that is moved into the path of the pawl on said clutch.

Referring to said drawings, the frame work of the machine may be of any suitable construction, preferably formed of side members 1, 1 connected by suitable cross pieces 2 to provide a rigid support for the operating parts. The frame is provided with legs and the mechanism is arranged and supported within this frame and driven in the usual manner by any suitable means (not shown).

The glue-applying devices, which are of any suitable construction preferably comprise a pair of glue-applying rollers, 3, 3 arranged in spaced relation on the top of the frame of the machine. The glue-applying rollers 3, 3 are driven by a belt 3' passing around a pulley on shaft 4, suitably mounted on the frame and suitably geared to the shaft 3" on which the glue rollers are mounted. Glue is supplied to the rollers 3 in any usual manner.

A carton flap-supporting device is positioned beneath and adjacent each glue roller to support the carton flaps in contact with said rollers. Each device comprises an arm 5 loosely mounted at one end thereof for pivotal movement on a stub shaft 6 journaled in any suitable manner in depending bracket 7 secured to one of the cross pieces 2. A shaft 8 is journaled in the free end of each of the arms 5 and secured to the inner ends of said shafts are flanges 10 to which are attached arcuate-shaped flap-supporting members 11, 11 which provide supporting surfaces for the carton flaps while the same are in contact with the glue-applying devices. Said members may be bolted to the flanges 10 by bolts 11' passing through openings in said members and flanges, so various sizes of flap-supporters may be employed, it being preferred to use flap supporters of substantially the same size as the flaps on the particular type of carton that is being sealed.

For exerting pressure on the carton flaps while the same are in contact with the glue-applying devices, and automatically providing for the adjustment of these devices to

accommodate flaps of different thicknesses, each of the arms 5 is provided with an extension 12 (Fig. 1) adapted to receive a set screw 13 that is held in adjusted position by a lock nut 13', said set screw being adapted to contact a small abutment 14 on the bracket 7, the set screw providing an adjustment to limit the vertical movement of the flap-supporting members 11. The distance between the flap-supporting members 11, 11 and the glue-applying rollers 3, 3 is slightly less than the thickness of the flaps to be operated on and each of the pivoted arms 5 has attached thereto one end of a coiled spring 15, the opposite end of which is attached in any suitable manner to a cross piece 2 of the frame so that the supporting members are yieldingly pressed against the flaps.

After the set screw 13 has been adjusted to limit the upward movement of the arms 5 in accordance with the thickness of the carton flaps, the coiled springs 15 will maintain a tension on the arms 5, the tension being brought into play when the flaps are engaged between the glue-applying and flap-supporting devices to thereby exert pressure on the flaps causing a squeezing or spreading action of the glue to insure complete coating of the flaps with a thin uniform layer of glue. Such a coating insures perfect sealing of the cartons and a great saving in glue.

The pivoted arms 5 and the coiled springs 15 provide leverage for the arcuate-shaped flap supporting members 11 whereby the latter are caused to hold the carton flaps against the glue rollers with great pressure. This leverage and pressure of the flap supporters is further increased by the arcuate-shaped members 11 which provide substantially a line contact between the carton flaps and the glue rollers 3. Each arcuate-shaped member 11 thus bears on a minimum area of the carton flap with increased pressure. Due to the increased pressure obtained by the flap supporters and the line contact provided by the arcuate-shaped member 11, this device will require a minimum amount of glue, while at the same time a more efficient sealing is obtained. Moreover, a thinner quality of glue may be employed, thus insuring that the package produced will be free from excess glue and discoloration. It will be observed that a comparatively simple construction is had by the present invention which provides new features of adjustability and interchangeability of parts. The device is highly efficient in operation, consists of a minimum number of parts, and decreases the cost of operation of devices of this character.

The carton conveyer mechanism may be of any suitable construction operating in the usual manner to continuously feed the car-

tons past the glue-applying and flap-supporting devices, the cartons having their flaps extended in the usual manner for engagement between said devices for application of the glue. The conveyer mechanism preferably comprises a pair of endless carriers 16 that carry the form supports 16', the edges of which are guided in suitable grooves 17 formed on the sides of upper and lower longitudinal supporting members 18 and 19 secured to the lowermost cross pieces 2. The forms 20 support the cartons 21, the side flaps 22 of which have been extended prior to positioning of the cartons on the forms or by the usual flap spreaders (not shown).

The forms 20 are each provided at one side thereof with a groove or recess 23 adapted to receive, when no carton is on the form, the free end of a finger 24 secured to the upper end of a vertical shaft 25 extending through an apertured guide 26 (Fig. 2) on the upper longitudinally-extending supporting member 18 and rotatably mounted at its lower end in a vertically adjustable bearing 27. The vertical shaft 25 is provided with an arm 28 which is rigidly secured to the shaft between the apertured guide 26 and the vertically adjustable bearing 27. The arm 28 is provided at the outer end thereof with a suitable aperture adapted to receive the hooked end of a reach rod 29 which extends transversely between the upper and lower longitudinally supporting members 18 and 19 respectively, the opposite hooked end of the reach rod engaging in a suitable aperture in one arm of a bell crank 31 secured on a spindle 32 rotatably mounted in adjustable step bearings 33 and 34. The other arm of the bell crank 31 carries a laterally movable stop member 35 adapted to be moved into and out of the path of travel of a projecting dog or pawl 36 pivotally mounted on one part 37' of a clutch 37 controlling the drive of the flap supporters.

The flap-supporting devices are driven from shaft 38 on which is secured the sprockets 38' around which pass the endless carrier chains 16 that carry forms 20. This shaft is driven from shaft 4 through chain 4' passing around sprockets 38'' on shaft 38. The shaft 38 has rigidly secured near one end thereof a sprocket 39 which drives by means of an endless chain 40 a sprocket 41 rigidly secured near one end of a shaft 42 suitably journaled in the frame. The shaft 42 also has keyed thereto a sprocket 43 which, by means of an endless chain 44, drives a sprocket 45 keyed at 45' (Fig. 6) to the hub 46 of the part 37 of the clutch, the part 37 being loosely mounted on a transversely-extending shaft 48 suitably journaled in the sides of the frame. The other part 37' of the clutch is keyed to the shaft 48, at 37''

and carries the dog 36. This dog 36 is carried by a pawl 51 (Fig. 6) which has an extension 51' on which the dog is mounted, said extension having a bearing in opening 51'' in the fixed part 37'. When the pawl 51, under the influence of spring 36' engages the recess 36'' formed in the loose part 37 of the clutch, the latter will be driven and the flap supporters operated. The spring 36' normally holds the dog in 75 position to keep the clutch closed.

The shaft 48 has keyed thereto sprockets 52, 52 which, by means of endless chains 53, 53, drive sprockets 54, 54 keyed to the outer ends respectively of the shafts 6, 6 80 which impart rotation to the flap-supporting shafts 8, 8, through sprockets 6' and 8'' on shafts 6 and 8, respectively, and sprocket chain 8' (Fig. 4).

During the operation of the machine, the cartons 21 are fed with their side flaps 22 extended to the glue-applying and flap-supporting devices. The flap-supporting devices are timed with relation to the travel of the carton conveyer mechanism (being 85 driven from shaft 38 around which the conveyer passes) in such manner as to bring the arcuate-shaped flap-supporting members 11, 11 into operative position at the time each of the cartons 21 passes below 90 the glue-applying rollers 3, 3. As the cartons 21 are fed past the finger 24, the latter is moved outwardly, thus rotating shaft 25 and by means of reach rod 29 moving stop member 35 out of the path of travel of dog 36, thus allowing the clutch 37 to operate in the usual well known manner to drive the shafts 6, 6 and 8, 8 and 8'. Suitable means are employed to move the finger back into the path of travel of the cartons, as spring 24' (Fig. 3) and after each carton has passed the finger 24 and the glue-applying and flap-supporting devices, the latter are prevented from rotating by the movement 100 of the stop member into the path of travel of the projecting dog 36 which latter, when rotated by engagement with the stop 35, moves the pawl 51 out of the recess 36'' and into the position shown in dotted lines in Fig. 7, thus opening the clutch and stopping the rotation of shaft 48, from which the flap supporters are driven.

In case any one or more of the cartons should not be properly placed on the formers, such cartons will engage the flap-supporting devices and move the same downwardly against the tension of springs 15, thus preventing damage to the flap-supporting devices.

In the operation of machines of this character where the feed of the cartons is rapid and continuous, it frequently happens that some of the forms are not provided with cartons to be operated upon by the various sealing and closing mechanisms of the ma- 125 130

chine, in which event the stop member 35 will move into the path of travel of the dog 36 causing the same to rotate to disconnect the two parts of the clutch and stop rotation of the flap-supporting members, the timing of the conveyer mechanism and the flap-supporting devices being such that the arcuate shaped flap-supporting members 11, 11 will be stopped in a position remote 10 from the glue-applying devices 3, 3.

In order to prevent damage to the stop member 35, by sudden contact with the projecting dog 36, the former is provided with a stem 55 the upper end of which extends 15 through an aperture in one arm of the bell crank 31 and is provided with a transversely extending cotter pin 56 (Fig. 8). The opposite end of the stop member is enlarged to provide a head 57 and interposed between 20 said head and the underside of the bell crank 31 is a coil spring 58 which forms a cushion for the stop member, and said spring is enclosed in a vertically depending sleeve 59 secured to the bell crank 31 and having 25 spaced relation with the head 57 of the stop member, said sleeve forming a housing for the spring to prevent displacement of or damage to the same.

While, for the purpose of illustration, one 30 expression of the inventive idea has been shown and described in detail, it is to be understood that the invention is not limited thereto and that the invention is susceptible of various mechanical expressions within 35 the limits of the appended claims.

What is claimed is:—

1. In a carton sealing machine, the combination of a glue roll, a rotatable arcuate-shaped flap supporting member disposed 40 adjacent to said glue roll, means for feeding cartons past said glue roll with their flaps extended for engagement with the same, and means for rotating said arcuate-shaped flap supporting member whereby the same is caused to engage and hold the carton flaps against the glue roll as the cartons are fed past the same.

2. In a carton sealing machine, the combination of a glue roll, a rotatable arcuate-shaped flap supporting member adjustably mounted adjacent to said glue roll, means for continuously feeding cartons past said glue roll with their flaps extended for engagement therewith, and means for rotating said flap supporting member whereby the same is caused to engage and hold a flap of each carton against the glue roll as the cartons are fed past the same.

3. In a carton sealing machine having a 60 main frame and a glue roll mounted thereon, the combination of conveyor mechanism for continuously feeding cartons past said glue roll with their flaps extended for engagement with the same, means for sup-

porting the carton flaps and holding the 65 same against said glue roll as the cartons are so fed, said means comprising an arm pivotally mounted on the main frame and an arcuate-shaped flap supporting member rotatably mounted on said arm, driving connections between the conveyor mechanism and the arcuate-shaped flap supporting member whereby the latter is rotated to flap-supporting position as each carton is fed past the glue roll, and means operable 70 by engagement with the cartons for maintaining said driving connections, said means being adapted to disconnect the driving connections in the absence of a carton.

4. In a carton sealing machine having 80 a main frame and a glue roll mounted thereon, the combination of means for feeding cartons past said glue roll with their flaps extended for engagement with the same, a device for supporting the 85 carton flaps and holding the same in engagement with the glue roll as the cartons are so fed, said device comprising an arm pivotally mounted on the main frame and an arcuate-shaped member rotatably mounted 90 on said arm, means for rotating said arcuate-shaped member into flap supporting position as each carton is fed past the glue roll, and means automatically adjusting said flap holding device on interruption in the 95 feed of said cartons.

5. In combination, a glue roll, an arcuate-shaped flap-supporting member, means for periodically moving said member into flap-engaging position, and means for yieldingly pressing said member toward said 100 glue roll.

6. In combination, a glue roll, an arcuate-shaped flap-supporting member, means for periodically moving said member into 105 flap-engaging position, and a spring acting to force said member toward said glue roll.

7. In combination, a glue roll, a pivoted arm, a flap-supporting member carried by the free end of said arm, a shaft for said 110 member, means for periodically moving said member into flap-engaging position, said means including a chain passing around said pivot and a second chain passing around said pivot and said shaft.

8. In combination, a glue roll, a pivoted arm, a flap-supporting member carried in the free end thereof, a spring normally tending to force said member into engagement with said roll, means for periodically 120 moving said member into flap-engaging position, said means including a drive to said pivot and a second drive from said pivot to said member.

In testimony whereof we have signed this 125 specification.

WM. L. TAYLOR.

CHARLES F. RICHARDS.
